FIG. 1 is a left side perspective view of the three way operated shaver of this design.

FIG. 2 is a top plan view thereof.

FIG. 3 is a right side elevational view of this design.

FIG. 4 is a bottom plan view thereof.

FIG. 5 is a left side elevational view of this design.

FIG. 6 is a rear view of this design.

FIG. 7 is a front perspective view of this design; and,

FIG. 8 is a top left perspective view of the product of this design with the crank extended from its at rest position to its ready for use position.

Note here, the broken lines that appear in several of the FIGURES are present for illustrative purposes only and form no part of the claimed design.
